(57) **CLAIM**

The ornamental design for a bottle body as shown and described.

DESCRIPTION

FIG. 1 is a perspective view of our new design for a bottle body;

FIG. 2 is a front elevation view thereof;

FIG. 3 is a rear elevation view thereof;

FIG. 4 is a left elevation view thereof;

FIG. 5 is a right elevation view thereof;

FIG. 6 is a top plan view thereof; and,

FIG. 7 is a bottom plan view thereof.

The dash-dash broken lines are shown for the purpose of illustrating parts of the article that form no part of the claimed design. The dot-dash broken lines in FIGS. 1 and 6 represent the boundaries of the claimed design and form no part thereof.

1 Claim, 4 Drawing Sheets
